UNITED STATES PATENT OFFICE

124,463

DESIGN FOR A DRESS

Germaine Monteil, New York, N. Y.

Application November 12, 1940, Serial No. 96,485

Term of patent 3½ years

To all whom it may concern:

Be it known that I, Germaine Monteil, a citizen of the United States, residing at 955 Fifth Avenue, New York city, in the county of New York and State of New York, have invented a new, original, and ornamental Design for a Dress, of which the following is a specification, reference being had to the accompanying drawing, forming part thereof.

The trimming appearing on the hood and scarf portion is composed of gold spangle embroidery.

The paillette trimmed hood portion is integrally attached to the dress.

I claim:

The ornamental design for a dress, substantially as shown and described.

GERMAINE MONTEIL.
